DIE FOR STAMPING OUT BLANKS, MORE PARTICULARLY FOR LEATHER GOODS

Filed Feb. 8, 1927

UNITED STATES PATENT OFFICE

FRANZ MERTINZ, OF VIENNA, AUSTRIA

DIE FOR STAMPING OUT BLANKS, MORE PARTICULARLY FOR LEATHER GOODS

Application filed February 8, 1927, Serial No. 166,783, and in Austria May 18, 1926.

This invention relates to dies for stamping out blanks, more particularly for leather goods, for instance shoe uppers, of the well-known type consisting of a core made of a block of wood, glued up pieces of veneer, metal or the like, around the peripheral surface of which band-shaped cutters are fixed by means of screws in such a manner that their cutting edges protrude beyond one or both faces of the core. In using dies of this kind, they are laid on the leather or the like and are operated by the core being given a blow with a hammer or placed under the plunger of a press.

Such dies have various drawbacks which render them less durable, detrimentally affect the accuracy of their shape and make them unreliable in operation. These properties are, however, indispensable in view of the present great variety and complicated form of the leather blanks to be stamped out, more particularly for shoe uppers. Thus, for instance, the screws connecting the cutters with the core take up the force of the blow exerted on the latter, so that the connection may easily become loosened and the cutters become detached from the core. For avoiding these drawbacks, according to the present invention the cutters are supported on the core by means of pieces of any suitable shape and made in any suitable manner projecting out of the plane of the cutters. In order to avoid the use of the not very reliable screw connection the cutters are fixed to the core by means of bolts having no thread and attached to the core by means of transverse pins. Where the core has narrow (tongue-like) parts, the dangers referred to are still greater and for this reason at such places the cutter is fixed by fixing means extending right through.

Further improvements relate to the cutters, the core, the elastic members releasing the stamped out blank from the core, and the punch of the press.

In the accompanying drawing a constructional example of the die according to the present invention is shown,

Figure 1 being a plan view,

Figure 2 a section on A—B of Fig. 1, partly in elevation,

Figure 3 a portion of the core with the cutter in vertical section,

Figure 4 a section on J, K of Fig. 3,

Figure 5 a section on C, D of Fig. 1,

Figure 6 a section on G, H of Fig. 5, and

Figure 7 a section on E, F of Fig. 1, to an enlarged scale.

The die consists of a core 1 which has the form of the leather blank to be stamped out and preferably consists of superposed pieces of veneer 2 glued together. Around the periphery of the said core band-shaped, flexible cutters 3 are so fixed that for instance they have their cutting edges 3', 3'' projecting beyond each face of the core.

In order that the means 4 for fixing the cutters to the core shall not be subjected to stressing, when the die is in use, tongues 5 are for instance stamped out of the cutters and bent over, which in the form of projections out of the plane of the cutter rest on the two faces of the core, preferably being let into the same. For this purpose the core is provided at suitable places with corresponding depressions 6. The stamping out and bending over of the tongues 5 may for instance be effected by subjecting the band-shaped cutters to a rapid local treatment with a hot jet of flame. The projections 5 may also be fixed in a suitable manner to the cutters 3 so and may be embedded within the core, as shown by way of example in Figs. 3 and 4, which represent a combination of the two improved forms.

Instead of the cutters 3 being fixed to the core 1 by means of screws (wood screws) they may be fixed by means of threadless bolts 4 (Figs. 1 and 5) which are fixed to the core 1 by transverse pins 7 extending through them. The bolts may be given any suitable cross-section, but in a preferred form a square bolt 4 is forced into a round hole 8 in the core (Fig. 6), as the bolt will then retain its position and the transverse pin 7 can readily be inserted through the bolt. Some of the bolts 4 may preferably have a square head 4', which enables them to be readily engaged with the tools, so that they may be easily released, should the die become jammed in the press.

At narrow tongue-like parts of the core 1 all the disadvantages of an insufficiently fixing of the cutters are more detrimental than at the other parts of the same. At such places 1' (Fig. 1) the cutters 3 are thus fixed by one or more fixing means extending right through the core, such as rivets 9 screws or the like, which clamp two parts of the cutter and the core lying between them together.

10 The rigidity of the cutter and disconnection to the core is the greater, the smaller the number of pieces from which the whole cutter is put together. For this reason the cutter is bent round more or less sharp edges (as for instance at 10 in Fig. 1), so that a single band-like cutter 3 extends right round the core, the connection of which with the core is thus made more simple. The cutter is closed at a single point only by means of an angle piece 11 (Fig. 1) or the like.

15 When the core 1 is built up of pieces of veneer glued together, which is to be recommended on account of the great rigidity and the absence of liability to warp and the smaller thickness of the core thus made possible, it is advisable to secure the layers from becoming detached from one another by the provision of screws 12, 13 (Figs. 1 and 2), which are screwed into the core from both faces of 20 the same, preferably staggered with respect to one another and overlapping each other in the transverse direction of the core.

25 For releasing the stamped out leather blanks or the like from the die cutter, elastic discs or cylinders for instance of rubber, have hitherto been fixed to the faces of the core by means of sunk screws, whereby they are deformed.

30 According to the present invention elastic members 14, (Figs. 1 and 2) of substantially hemispherical shape are used, the entire base of which is sunk in depressions 15 in the core and which are fixed to the core by means of screws 16 which are sunk in the said members, without their being deformed. Preferably a hole 17 is provided in the rubber member, in which there is a widened part 18, into which the head 16' of the screw 16 fits. With this constructional form the stamped out 35 leather blanks and the elastic bodies are not so liable to be damaged.

35 The provision of punches, such as numeral punches or the like, for such dies has already been proposed. The punches punch a mark into the blank, when it is being stamped out. According to the present invention a yielding punch is provided. As shown in Fig. 7 a smooth sleeve 19 (i. e. a sleeve having no projecting parts) contains the stamp 20 and 40 a compression spring 21. The other part 20' of the punch rests against an inwardly directed flange 22 and the spring against an inwardly bent part 23 of the sleeve 19. The whole arrangement forms a complete unit which, owing to the smooth surface of the sleeve 19,

can simply be slid into a hole in the core 1. The punch acts on the blank of the pressure which is independent of the stamping pressure and which corresponds to the strength of the spring, so that the blanks are not liable to be damaged, which is of special importance in the case of fine leather. 70

What I claim is:

1. A die for stamping out blanks, more particularly for leather goods, comprising a core 75 and band-shaped cutters which are fixed to the peripheral surface of said core, project beyond the face of said core and are provided with projections extending out of said cutters and resting against said core. 80

2. A die as claimed in claim 1, in which the projections of the cutters are embedded in the core.

3. A die as claimed in claim 1, in which the cutters are fixed to the core by bolts having no 85 thread, the latter being fixed to the core by means of transverse pins entirely sunk into the core.

4. A die as claimed in claim 1, in which at the narrow parts of the core, cutters are fixed to the same by fixing means extending right through said core and clamping together two parts of the cutters and the core lying between them. 90

5. A die as claimed in claim 1, in which the cutter extends right round the core and is fixed to said core in a single piece. 95

6. A die as claimed in claim 1, in which a veneered core is held together by screws fitted in the core from both faces and staggered with respect to one another. 100

7. A die as claimed in claim 1, in which a resilient stamp comprising an outer sleeve without projecting parts is sunk into a hole on the face of the core. 105

8. A die as claimed in claim 1, in which the projections are in the form of flat pieces connected with the cutter.

9. A die as claimed in claim 1, in which the projections are in the form of tongues bent 110 out of the cutter material.

In witness whereof I have hereunto signed my name.

FRANZ MERTINZ.
